UNITED STATES PATENT OFFICE.

FRANK B. DAVIDSON, OF MARSEILLES, ILLINOIS, ASSIGNOR TO HOWE AND DAVIDSON COMPANY, OF EAST ORANGE, NEW JERSEY, A CORPORATION OF NEW JERSEY.

PAPER-TRAY.

No. 843,933.

Specification of Letters Patent.

Patented Feb. 12, 1907.

Application filed March 31, 1904. Serial No. 200,948.

To all whom it may concern:

Be it known that I, FRANK B. DAVIDSON, a citizen of the United States, of Marseilles, in the county of Lasalle and State of Illinois, have invented certain new and useful Improvements in Paper-Tray; and I do hereby declare that the following is a full, clear, and exact description thereof, reference being had to the accompanying drawings, and to the letters of reference marked thereon, which form a part of this specification.

This invention relates to improvements in trays and other like receptacles made of paper or other flexible sheet material, provided with a flat bottom and a rim surrounding said bottom, and the tray may or may not be provided with radial partitions extending from the rim to the center of the tray.

The device herein illustrated is especially applicable for use as a tray for packing in pails candies and like merchandise, and when used in this manner the trays are filled and placed in a candy-pail one over the other, said trays thus supporting each other in the pail and serving as horizontal separators or partitions by which the layers of candy in the pail are separately supported. A device having the same features of construction may, however, be used for other purposes.

As shown in the drawings, Figures 1 and 2 are the two parts of a blank constituting when folded in proper form a complete tray. Fig. 3 is a blank which is folded to constitute radial partitions which divide the tray into a plurality of radial compartments. Fig. 4 is a bottom plan view of the tray. Fig. 5 is a top perspective view of the tray. Fig. 6 is a fragmentary central view of the central part of the blank when partially folded. Fig. 7 is a horizontal section taken on line 7 7 of Fig. 5. Fig. 8 is a fragmentary vertical section taken on line 8 8 of Fig. 5. Figs. 9 and 10 illustrate the two parts of the blank of a form of tray varied from that previously described in the manner of fastening the rim to the bottom. Fig. 11 is a plan view of the set-up tray. Figs. 12 and 13 are fragmentary sections taken, respectively, on lines 12 12 and 13 13 of Fig. 11. Fig. 14 is a fragmentary plan view of a further modified form of the locking-flap of the rim. Fig. 15 is a fragmentary plan view showing the manner of

interlocking the rim shown in Fig. 14 with the bottom wall. Fig. 16 is a section taken on line 16 16 of Fig. 15.

A complete tray embodying the several features of my invention, such as shown in Fig. 5, consists of three separate parts or blanks A B C. The part A consists of a flat sheet of material made of the contour of the tray-rim. It is shown as circular in the present instance and constitutes the bottom of the tray. The part B constitutes the rim of the tray and embraces an elongated strip B', having at its lower edge a plurality of integral outwardly-tapered contiguous projections B², which are divided from the body of the strip by score-lines b and on which score-lines said projections are adapted to be folded to bring said projections at substantially right angles to the body portion. Said strip B' is adapted to be folded into circular or other form to correspond to the shape of the tray-margin, and its ends are secured together, preferably by means of a locking-tongue b', at one end of which engages a locking-slit b² adjacent to the other end thereof. The projections B² of said strip B' when the latter surrounds the bottom in the manner stated extend beneath said bottom and their extremities are inserted upwardly through a series of slits a in said bottom, the extreme ends of the points being thus located on the upper face of said bottom. The strip B' is provided between the triangular projections B² with a plurality of flaps B³, which, as herein shown, entirely fill the spaces between adjacent projections B². Said projections B² are adapted to be folded at right angles to the strip B' on the score-lines b and when the rim is in place rest upon or overlap the bottom A, and thus lock the inner margin of said bottom between the projections B² beneath the same and the flaps B³ above the same in the manner more clearly shown in Figs. 4 and 8. The two parts A and B constitute when set up a complete tray having a single unobstructed compartment and may be thus used for some purposes. The blank C is so formed as to constitute when folded a divider having a flat wall C' adapted to rest on the bottom of the tray, as shown in Fig. 8, and provided with a plurality of radial partitions C², which, as herein shown, are formed by upwardly-folded parts of said wall, though they may be otherwise for. The particular form of separators

herein shown is a desirable one, inasmuch as it is so constructed as to be readily and economically made. The said blank C, from which the divider is formed, is provided with 5 two sets of score-lines c c' , there being three parallel lines in each set, and the said two sets of score-lines intersect each other at the center of the blank. Between the central and two outside score-lines of each set are formed 10 rectangular partition-sections c^2 c^2' , which are adapted to be folded upwardly at right angles to the blank and brought into contact with each other to constitute the partitions C^2 , while the parts c^3 of the blank in the angles 15 between said intersecting score-lines constitute the bottom wall C' of the divider and an inner bottom for the tray. The central part of the blank C in the rectangular space inclosed by the outer intersecting score-lines 20 c' is divided by two right-angle intersecting lines of severance c^4 to constitute four rectangular tabs c^5 c^5' . Said tabs are joined to opposite partition-sections c^2 , but are divided from the partition-sections of the other 25 partitions by cuts or severance-lines c^7 , said cuts or severance-lines, together with the intersecting cuts or severance-lines c^4 , freeing the tabs c^5 at all their margins, except the margins at which they are joined to 30 the partition-sections before referred to. Score-lines c^6 c^6' extend across the bases of the tabs. When the divider is to be set up or formed from the blank cut and scored in the manner described and shown in Fig. 3, the 35 companion partition-sections c^2 c^2' are folded flatwise against each other, said sections being folded upwardly from the blank on the score-lines c' . The tabs c^5 at the center of the blank are folded at right angles to the 40 partition-sections to which they are joined and are inserted between the partition-sections at right angles to the partitions carrying the tabs, thereby constituting interlocking connections between the inner ends of said partitions when the latter are set up, as more 45 clearly shown in Fig. 7. The manner in which the tabs c^5 are inserted between the sections of adjoining partitions is more clearly shown in Fig. 6, said figure indicating the 50 parts when the blank is held bottom up and opposite halves of the same bent downwardly to separate the partition-sections between which the tabs are to be inserted, so as to enable the tabs to be folded outwardly into contact therewith, as fully set forth in my prior 55 United States Letters Patent, No. 780,325, issued January 17, 1905.

In setting up the completed tray (shown in Fig. 5) the rim section or portion is closed 60 about the bottom A and the triangular projections B^2 inserted into the slits a and the flaps B^3 lapped over the upper face of said bottom. The rim-strip B' is then locked about the said bottom, either by the tongue- 65 and-slit construction shown or otherwise.

Thereafter the divider is folded in the manner described and placed within the rim upon the upper face of the bottom of the tray. The divider fits so closely within the tray as to be held therein by friction alone. The 70 ends of the partitions engage the rim and support the rim in a vertical position. The score-lines b at the bases of the triangular projections B^2 and flaps B^3 are preferably made straight, so that when the rim is formed 75 it will assume a polygonal shape, as distinguished from a true circle. This construction is preferable inasmuch as it prevents one tray telescoping into another when said trays are placed one upon the other in a pail or like receptacle.

It will be understood that the tray may be made of other shape than circular, and when so made the parts of the blank will be correspondingly modified. Other changes in the 85 structural details may be made without departing from the spirit of the invention, and I do not wish to be limited to such details except as hereinafter made the subject of specific claims.

The modification shown in Figs. 9 to 16, inclusive, is not provided with a divider, but consists merely of a flat bottom and a rim surrounding the bottom and locked thereto. The tray shown in said figures is composed of a rim-blank D and a bottom-blank E. Said rim-blank is provided at one of its margins with a plurality of flaps or projections D' D' , joined to the margin of the rim by score-lines d . Said projections or flaps are formed by 90 slitting the blank D inwardly from one margin thereof, the slits d' dividing the flaps or projections D' , which latter are shown as rectangular. The blank is provided at each end with a locking-tongue d^2 , each adapted to 95 enter a slit d^3 at the opposite end of the blank. The bottom-blank E, shown as made circular, is provided with a circular series of crescent-shaped slits e , which form a plurality of tongues e' . The rim-blank is fitted 100 around the bottom-blank, with the flaps or projections D' arranged alternately above and below said margins in overlapping relation, and the tongues e' are bent or folded alternately above and below the bottom-blank 105 for engagement with the inner ends of said projections or flaps of the rim. When the flaps of the rim are engaged with the tongue in the manner described and the rim is locked in place by engagement of the 110 tongues d^2 with the slits d^3 , the rim is held securely in place, first, by reason of the fact that the abutting relation of the inner margins of the rim-flaps with the bases of the 115 tongues prevents the rim from shifting inwardly, and, secondly, by reason of the fitting of the rim-flaps alternately above and below the margin of the bottom, said rim is prevented from rising away from the bottom.

In Figs. 14, 15, and 16 the flaps D' are 120

shown as provided with extensions d^4 , which extend beyond the bases of the tongues e' on the side thereof opposite to that which said tongue is folded from the plane of the bottom, as clearly shown in Fig. 16. The relation of said extension with the tongue serves to considerably strengthen the connection between the rim and bottom.

I claim as my invention—

10 1. A tray comprising a flat bottom and a rim consisting of a strip having locking means at its ends and provided with a plurality of projections or flaps which are folded beneath the said bottom and enter a series of slits in said bottom, said rim being provided between said projections with a plurality of flaps which overlap the margin of the bottom.

20 2. A knockdown paper-tray consisting of three parts, to wit, a flat circular bottom, a rim consisting of a straight strip bent into circular form, and which has on its lower edge a plurality of flaps or projections adapted for interlocking connection with said bottom and is provided at its ends with interlocking parts by which they are secured together, and a divider resting on said bottom within the rim and consisting of a rimless sheet provided with a plurality of integral upwardly-folded parts forming radial parti-

30 3. A tray comprising a flat bottom, a rim and a divider comprising a bottom part which rests on the bottom of the tray, said divider being provided with a plurality of

integral, radial partitions formed by folding upwardly parts of the divider, each partition comprising parallel partition-sections which are folded into contact with each other, and are provided at their inner ends with tabs for locking said partitions together.

40 4. A tray comprising a flat bottom, a rim comprising a strip provided with a plurality of projections or flaps which engage slits in said bottom, and with flaps adapted to overlap said bottom, and a divider comprising a bottom which rests on the bottom of the tray and is provided with a plurality of integral, radial partitions formed by folding upwardly parts of said divider.

45 5. A tray comprising a flat bottom, a rim consisting of a strip provided with a plurality of flaps or projections adapted to engage slits in said bottom, and a divider comprising a bottom which rests on the bottom of the tray, and is provided with a plurality of integral radial partitions which are formed by folding upwardly parts of said divider, said partitions being interlocked with each other at their inner ends and fitting closely within the rim at their outer ends.

50 In testimony that I claim the foregoing as my invention I affix my signature, in presence of two witnesses, this 21st day of March, A. D. 1904.

FRANK B. DAVIDSON.
